UNITED STATES PATENT OFFICE.

JOHN S. WILLIAMSON, OF BALTIMORE, MARYLAND, AND HERBERT L. BEACH, OF PITTSBURGH, PENNSYLVANIA.

DESIGN FOR A COMBINATION SIGNAL AND TAIL LIGHT.

Application filed December 21, 1923. Serial No. 8,116. Term of patent 3½ years.

To all whom it may concern:

Be it known that we, JOHN S. WILLIAMSON and HERBERT L. BEACH, both citizens of the United States of America, residing, respectively, at the city of Baltimore, State of Maryland, and Pittsburgh, county of Allegheny, State of Pennsylvania, have invented a new, original, and ornamental Design for a Combination Signal and Tail Light, of which the following is a specification, reference being had to the accompanying drawings, forming part thereof.

In the drawings:

Fig. 1 is a front elevation of the combi-

nation signal and tail light embodying our invention.

Fig. 2 is a side elevation.

Fig. 3 is a top plan.

Fig. 4 is a bottom elevation.

What we claim is:

The ornamental design for a combination signal and tail light, substantially as shown.

Signed at Baltimore, State of Maryland, this 20 day of December, 1923.

JOHN S. WILLIAMSON.
HERBERT L. BEACH.
